UNITED STATES PATENT OFFICE.

JAMES M. MERRITT, OF BUFFALO, NEW YORK, ASSIGNOR TO HIMSELF
AND JOHN W. A. MEYER, OF SAME PLACE.

STENCIL NUMBERING APPARATUS.

Specification forming part of Letters Patent No. **56,674**, dated July 24, 1866.

To all whom it may concern:

Be it known that I, JAMES M. MERRITT, of the city of Buffalo, in the county of Erie and State of New York, have invented a new and Improved Stencil Apparatus for Numbering; and I hereby declare that the following is a full and exact description thereof, reference being had to the accompanying drawings, making part of this specification, in which—

Figure 1 is a plan view, and Fig. 2 a transverse section, of my apparatus.

Like letters of reference indicate corresponding parts in both figures.

My invention consists in mounting in a suitable frame or plate a series of movable slides each of which has the integral figures from 0 to 9 cut through it in the manner of stencil marking-plates, said frame being provided with apertures corresponding in size and with the positions occupied by the figures on the slides, and with a guide or stop to regulate the adjustment of the figures in a proper position when arranging them to form the numbers required, and with a suitable lip or thumb-piece for holding the apparatus when used.

As shown in the drawings, A represents the frame-plate, having the figure-openings b c d and the abbreviation "No." at the left thereof. The back of the plate is provided with lips e e, preferably made by turning over an edge of the thin metal used for stencil-plates, but may be formed by straps, loops, or in any other manner to produce an equivalent effect. These lips form ways in which the figure-slides 1 2 and 3 rest and are moved.

The slides consist of narrow strips of metal, each having the nine digits and the cipher (0) stencil-cut through them in a vertical column. These slides may be of any number, according to extent of numbering required, and being arranged side by side in the frame A, the figures on the right-hand one signify units, those of the next tens, the next hundreds, and so on according to arithmetical progression. Arranged as shown, with three figure-slides, the highest sum attained is 999; with four it would be 9,999; with five, 99,999.

The method of operating is exceedingly simple. Beginning with the slides drawn down so that the solid metal at the top of each closes

the apertures b c d, the first (1) is moved upward until the figure 1 is exposed. When this has been marked the slide is raised by inserting the point of a pencil or any blunt instrument into the figure immediately below the frame and sliding it upward until the guard f stops it, which exposes figure 2. This process being repeated for each figure of slide 1, the next (2) is brought into use in the same manner, the first being kept stationary at figure 1 till the numbers from 10 to 19 inclusive have been produced, when figure 2 of slide 1 is brought into use for another series of tens, and so on until 99 is reached, when slide 3 is employed to produce 100.

The thumb-piece B, which forms the upper part of the plate A, enables the person using it to conveniently hold the apparatus by pressing it upon the article to be marked while the change of figures is made and the brush applied.

The guide f is a straight-edged bar, which strengthens the lower edge of the plate and stops the slides when they are moved upward to change the number in exactly the position required to bring all the figures on a line with the letters "No."

The slides are moved by inserting any blunt-pointed instrument into the figure below the guide f and moving it upward as far as the guide will permit.

For revenue assessors, inspectors, packers, and others who have occasion to mark progressive numbers this affords a convenient and very portable apparatus, and one by the use of which correctness in numbering is almost certainly insured.

What I claim as my invention, and desire to secure by Letters Patent, is—

The improved stencil numbering apparatus herein described, consisting of the plate or frame A, with apertures b c d, and the figure-slides 1 2 3 and guide f, or its equivalent, constructed and arranged substantially as described.

JAMES M. MERRITT.
